UNITED STATES PATENT OFFICE.

GUSTAF PERSON WERN, OF BROOKLYN, ASSIGNOR TO THE PELHAM HOD ELEVATING COMPANY, OF NEW YORK, N. Y.

CHAIN HOD-ELEVATOR.

SPECIFICATION forming part of Letters Patent No. 527,305, dated October 9, 1894.

Application filed January 18, 1894. Serial No. 497,266. (No model.)

To all whom it may concern:

Be it known that I, GUSTAF PERSON WERN, of Brooklyn, in the county of Kings and State of New York, have invented certain new and useful Improvements in Chain Hod-Elevators, of which the following is a full, clear, and exact description.

The object of the invention is to provide certain new and useful improvements in chain hod-elevators, whereby the driving shafts are securely held in proper position to prevent undue friction and binding in the bearings.

The invention consists of certain parts and details, and combinations of the same, as will be fully described hereinafter and then pointed out in the claims.

Reference is to be had to the accompanying drawings, forming a part of this specification, in which similar letters of reference indicate corresponding parts in all the figures.

Figure 1 is a side elevation of the improvement with parts in section. Fig. 2 is a front elevation of the same with parts in section. Fig. 3 is a sectional plan view of one of the standards, on the line 3—3 of Fig. 1; and Fig. 4 is a perspective view of the bottom brace.

In the drawings only the upper part of the entire hod elevator is shown, as the lower part is similarly constructed, and hence further description of the same is not deemed necessary.

The upper part of the hod elevator is provided with a frame A, having two standards A' and A² supported on longitudinally extending beams B and B' respectively, set on suitable supports in the upper part of the building and connected with each other by a bottom cross brace B². Each of the standards A' and A² is constructed of two T-irons A³ and A⁴, as is plainly shown in Figs. 1 and 3, the said T-irons being parallel in their upper part, and bent outward at their lower ends to form a foot resting on the beams B, B', as is plainly shown in said Fig. 1. The standards A' and A² are connected with each other near their upper ends by a transverse brace C hereinafter more fully described. In the frame A is journaled the driving shaft D, provided at its outer ends with the usual crank arms E, taken 50 hold of by the operators, for turning the said

shaft D. The outer ends of the shaft D are journaled in bearing boxes F, each preferably made of brass cast in one solid piece and having its outer surface rounded, as is plainly illustrated in Fig. 2. Each box F is seated 55 with its lower half in a corresponding shaped block G, bolted or otherwise secured to the T-irons A³ and A⁴ of the corresponding standard A' or A², the said block G thus holding the parallel parts of the two T-irons A³ and A⁴ proper distances apart. On the top of each box F rests the lower concave end of a block G' formed with an interior screw thread engaged by a screw bolt G², hung on a pivot G³ secured in a block G⁴ bolted to the T-irons A³ 60 and A⁴, as is plainly shown in Figs. 1 and 2. Now, it will be seen that each bearing F, with its blocks G and G' forms a universal joint, so that any wobbling motion of the shaft D or of the frame or the individual parts thereof, 70 will not cause the shaft D to bind in its journal boxes F, nor the latter in their supports, the blocks G and G'.

By the arrangement described, the journal boxes F can be quickly removed from the end 75 of the shaft by screwing the upper block G' upward on the screw G² and then slipping the box off the end of the shaft, it being understood that the corresponding crank arm E has been previously removed. A new box F 80 can then be readily inserted in place, seated on the fixed block G and again engaged by the adjustable block G', by screwing the latter downward on its screw. On the shaft D is secured the usual sprocket wheel D', under 85 which passes a sprocket chain H, extending upward and passing over a sprocket wheel H' fastened on the driving shaft I, carrying the drum I', over which passes the elevating chain K provided with transverse rods K' to 90 carry the hods. This shaft I is provided at its ends with bearing boxes F' similar in construction to the bearing boxes F previously described, the said boxes F' being held in a casing L comprising the fixed blocks L' bolted 95 to the upper ends of the T-irons A³ and A⁴ of the corresponding standards A' and A², as is plainly shown in the drawings. On this block L' is pivoted the cap L² by a bolt L³ passing into the block L'. See Fig. 1. It will 100

be seen that the boxes F' in the casings L can turn sufficiently to compensate for any wabbling motion of the shaft I, thus preventing binding of the shaft I in its bearings.

- 5 The transverse brace C previously mentioned is provided with the two bars C' and C², terminating in bolts C³, passing through apertured cross pieces C⁴, abutting against the outer faces of the two corresponding 10 T-irons A³ and A⁴. A nut C⁵ screws on the outer threaded end of each bolt C³ to abut against the outer face of the cross piece C⁴, to securely fasten the latter in place and hold the bars C' or C² in a proper position. 15 Each bolt C³ rests on a bolt C⁶ connecting the two T-irons A³ and A⁴ of the corresponding standards A' and A² together.

The two bars C' and C² are connected with each other by diagonal braces C⁷ and C⁸, as is 20 plainly shown in Fig. 2. The ends of each of said braces are formed with plates C⁹, adapted to abut against the inner face of the corresponding T-irons A³ and A⁴, the said plates being directly opposite the corresponding cross 25 plate C⁴. Each of the plates C⁹ is formed with a notch adapted to pass upon the corresponding bolt C³ of the bars C' and C², as will be readily understood by reference to Fig. 1. Thus, when the brace C is in position and the 30 nuts C⁵ are screwed up, the several parts of the brace are securely held in position and form a very strong connection for the two standards A' and A², to prevent lateral displacement of the said standards. By this 35 arrangement the driving shafts D and I are not liable to bind in their bearings and should a heavy strain be exerted on the said shafts, their boxes F F' can move sufficiently in their bearings to prevent binding.

40 The bottom brace B² for connecting the beams B, B' with each other is preferably made of a single piece of cast iron, as is plainly shown in Fig. 4, and is provided with diagonal arms each formed at its outer end with a 45 flange B³ abutting against the inner face of the corresponding beam B, or B'. Each flange B³ is formed in its under side with a notch to engage a bolt B⁴ extending transversely through the corresponding beam B 50 or B'.

By the arrangement described, the frame A is very strongly constructed, so that the various parts of the machine are securely held in place. On the shaft D is also secured 55 the usual ratchet wheel D² engaged by a pawl D³ held on the standard A² to prevent an accidental return movement of the said shaft.

Having thus fully described my invention,

I claim as new and desire to secure by Letters Patent—

60

1. In a chain hod-elevator, the combination with a frame having standards connected with each other, of fixed blocks attached to the said standards, bearing boxes having curved exterior surfaces seated in the said fixed blocks, a shaft journaled in the said bearing boxes, adjustable blocks engaging, with their concave under surfaces, the said bearing boxes opposite the fixed blocks, and pivoted screw rods on which screw the said adjustable blocks, substantially as shown and described.

70

2. In a chain hod-elevator, the combination with a frame having standards connected with each other, of fixed blocks attached to the said standards, bearing boxes having curved exterior surfaces seated in the said fixed blocks, a shaft journaled in the said bearing boxes, adjustable blocks engaging, with their concave under surfaces, the said bearing boxes opposite the fixed blocks, pivoted screw rods on which screw the said adjustable blocks, and blocks fixed in the said standards and carrying the pivots for the said screw rods, substantially as shown and 80 described.

75

3. A chain hod elevator, provided with a frame comprising two standards, each formed of two T-irons, blocks for fastening the T-irons together, a transverse brace for connecting the standards with each other, the said brace comprising two horizontal bars formed with bolts at their ends, plates engaged by the said bolts and bearing against the said plates, and diagonal braces formed 90 with flanges having notches engaging the said bolts, substantially as shown and described.

95

4. A chain hod elevator, provided with a frame comprising two standards, each formed of two T-irons, blocks for fastening the T-irons together, a transverse brace for connecting the standards with each other, the said brace comprising two horizontal bars formed with bolts at their ends, plates engaged by the said bolts and bearing against the said plates, diagonal braces formed with flanges having notches engaging the said bolts, and bolts connecting the T-irons with each other and adapted to form a rest for the bolts of the horizontal bars, substantially as 100 shown and described.
